UNITED STATES PATENT OFFICE.

JOHN C. INGRAM, OF CAMERON, WEST VIRGINIA, ASSIGNOR OF ONE-HALF TO WALTER H. LOPER, OF CAMERON, WEST VIRGINIA.

WRENCH.

1,149,060.

Specification of Letters Patent.

Patented Aug. 3, 1915.

Application filed May 3, 1915. Serial No. 25,380.

To all whom it may concern:

Be it known that I, JOHN C. INGRAM, a citizen of the United States of America, and resident of Cameron, county of Marshall, 5 and State of West Virginia, have invented certain new and useful Improvements in Wrenches, of which the following is a specification.

This invention relates broadly to a combination tool, and more particularly to a tool 10 of the wrench type.

The primary object of the invention is to provide a tool having a fixed jaw and a movable jaw, the latter being provided with 15 a pivoted arm by means of which a powerful gripping force may be exerted upon the object engaged by said jaws.

A further object of the device is to provide means whereby said movable jaw may 20 be locked from movement away from the stationary jaw. And a still further object of the invention is to provide a tool of the character mentioned the handle of which is adapted to be used as a hammer.

25 With these and other objects in view, the invention resides in the features of construction, arrangement of parts, and combination of elements which will hereinafter be fully described, reference being had to 30 the accompanying drawings, forming part of this specification, in which—

Figure 1 is a side elevation of my invention; and Fig. 2 is an under-side view of the same.

35 Referring to said drawings, 1 indicates a fixed jaw having a shank 2 of a peculiar novel form formed integral therewith, the opposite end of said shank being disposed at substantially a right angle to the body there- 40 of and being enlarged or thickened to provide a handle portion 3 which may be used as a hammer. Pivoted to the shank 2 slightly in the rear of said jaw 1, is the shank 4 of a relatively movable jaw 5. Piv- 45 otally connected to the rear end of said shank 4 is the end of an arm 6 which has formed on its free end a plurality of aligned rings 7 adapted to be engaged by the fingers of the hand which holds the handle 3. The 50 arm 6 may have notches 8 formed on either or both sides thereof, said notches being adapted to receive the adjacent parallel portions of a substantially U-shaped guide or keeper 9 through which said arm 6 extends,

the parallel portions of said keeper being 55 rigidly attached to the shank 2.

As is obvious, when an object is to be engaged by the jaws of my tool, said jaws are separated by thrusting the arm 6 forward, causing the movable parts to assume sub- 60 substantially the positions shown in dotted lines in Fig. 1. When the object to be engaged is disposed between the jaws, the arm 6 is drawn rearward to cause the jaws to grip said object, whereupon the latter may be ro- 65 tated as by a wrench of any ordinary type.

The opposing jaws may be made in any of numerous widely varying forms, adapting the device for a variety of uses.

The shank 2 has an angular or down- 70 wardly bowed form at a point slightly in the rear of the pivotal connection of the shank 4 therewith, the latter being disposed across said shank 2. And, since the arm 6 recrosses said shank 2, it will be seen that the device 75 is substantially of lazy-tongs shape. This form of the device, coupled with the ar- rangement of the gripping rings 7 closely adjacent to the handle 3 provides not only means whereby a powerful gripping force 80 may be applied to an object interposed be- 85 tween the jaws, but also whereby entrance may be had to close places, or places which are difficult of access with tools of ordinary types.

What is claimed is—

1. A tool of the character described comprising a shank having a fixed jaw at one end and an angularly disposed handle at the other end, said shank being downwardly bowed at the rear of said jaw, a second shank crossing and pivotally connected to the first mentioned shank at a point slightly in the rear of said jaw, a jaw carried by said second shank and adapted to coöperate 90 with the first mentioned jaw, an arm piv- 95 otally connected to the rear end of said sec- 100 ond shank and recrossing the first mentioned shank, a keeper carried by the first shank and having said arm freely movable there- through, and gripping means carried by said arm disposed adjacent to said handle.

2. A tool of the character described comprising a shank having a fixed jaw at one end and an angularly disposed handle at the other end, said shank being downwardly bowed at the rear of said jaw, a second shank crossing and pivotally connected to

- the first mentioned shank at a point slightly in the rear of said jaw, a jaw carried by said second shank and adapted to coöperate with the first mentioned jaw, an arm 5 pivotally connected to the rear end of said second shank and recrossing the first mentioned shank, a keeper carried by the first shank and having said arm freely movable therethrough, gripping means carried by 10 said arm disposed adjacent to said handle, and notches formed in said arm adapted to receive therein a portion of said keeper for maintaining the movable parts in adjusted position.
- 15 3. A tool of the character described comprising a shank having a fixed jaw at one end and an angularly disposed handle at the other end, said shank being downwardly bowed at the rear of said jaw, a second

shank crossing and pivotally connected to 20 the first mentioned shank at a point slightly in the rear of said jaw, a jaw carried by said second shank and adapted to coöperate with the first mentioned jaw, an arm pivotally connected to the rear end of said second shank and recrossing the first mentioned shank, a keeper carried by the first shank and having said arm freely movable therethrough, a finger grip carried by the rear 25 end of said arm and closely associated with 30 said handle, and means for securing the movable parts in adjusted position.

In testimony whereof, I affix my signature in presence of two subscribing witnesses.

JOHN C. INGRAM.
